UNITED STATES PATENT OFFICE

125,271

DESIGN FOR A RESTAURANT BUILDING

Walter M. Houston, Berkeley, Calif.

Application February 28, 1940, Serial No. 90,573

Term of patent 14 years

To all whom it may concern:

Be it known that I, Walter M. Houston, a citizen of the United States of America and a resident of the city of Berkeley, county of Alameda, State of California, have invented a new, original, and ornamental Design for a Restaurant Building, of which the following is a specification, reference being had to the accompanying drawing, forming a part thereof, and in which the Figures 1, 2, 3 and 4 represent the front, top and end views, respectively, of the building in accordance with my new design.

The rear side of the building is plain except for necessary doors and windows.

I claim:

The ornamental design for a restaurant building, substantially as shown and described.

WALTER M. HOUSTON.
